UNITED STATES PATENT OFFICE.

SWAN NELSON, OF CHICAGO, ILLINOIS.

POP-CORN MACHINE.

Application filed October 14, 1927. Serial No. 226,179.

My invention relates to machines for popping corn, and more particularly to such machines as are used in windows or on counters as an animated display, and my main object is to provide a machine of this kind which employs a simple mechanism.

A further object of my invention is to construct the novel machine to occupy a minimum of space consistent with the nature of its construction and operation, in order that it may take up a small amount of room wherever installed.

A still further object of the invention is to design a working element which is attractive and fascinating to the observer, whereby to make the display draw the attention of spectators and patrons.

Another object of the invention is to employ a vessel of a transparent material, whereby the working and effect of the machine may be more fully observed.

A final but nevertheless important object of the invention is to construct the novel machine with few parts, so that its cost may be low and its handling easy.

With the above objects in view and any others that may suggest themselves from the specification and claims to follow, a better understanding of the invention may be gained by reference to the accompanying drawing, in which—

Figure 1 is an elevation of the novel machine, partly in section; and

Fig. 2 is a plan view of the same.

It is a familiar fact that machines used for popping corn with the effect of a working display are usually complicated in their mechanism and occupy a considerable amount of space for which reasons they are generally expensive. It has been my belief that a suitable machine with attractive display features could be produced at a small expense without the use of many parts or the sacrifice of attractive value. I have, therefore, designed the novel machine to accomplish the objects above contemplated in an efficient manner.

Referring specifically to the drawing, 5 denotes the vessel constituting the main element of the machine. This vessel is part-circular, with high side walls and a curved bottom 6, giving the suggestion of a trough. The vessel is suitably supported on legs or posts 7 over a tray 8, which receives the popped corn; or, the machine may be installed in a window or glass counter which

becomes piled up with the popped corn as the machine continues to produce it. Under the vessel 5 is suitably disposed a gas burner 9, but I do not wish to limit myself to this type of burner as I may use an oil burner, or an electric heating element immediately under the vessel to heat the same.

Near the upper part of the vessel are formed bearings 10 to receive a cross-shaft 65 11 which spans the vessel. The cross-shaft is extended to the front as shown, or to the rear if it is so preferred, to receive a chain-and-sprocket drive 12, 13. This drive may receive its motion from an electric or other 70 motor, suitably geared to operate the cross-shaft 11 at slow speed.

The cross-shaft 11 receives a two-armed spider 14 at whose ends are formed grid members 15. Each of these is substantially 75 rectangular in form and formed with a series of parallel bars 15^a disposed in a direction longitudinal of the spider. The grid members are so designed that they may course through the lower portion of the 80 vessel singly as the spider is rotated, with the outermost cross bar 15^b very nearly in contact with the bottom of the vessel; also, the bars 15^a are so spaced as to clearly permit the passage of popping corn, but to bar 85 the transformed product, that is, the popped corn, such product usually being several times the size of the popping corn. Thus, as the grids sweep through the bottom of the vessel they will not take with them the popping corn, but only the popped corn.

In order that the grids may more readily dump the popped corn as they emerge from the vessel they are deflected rearwardly, considering the motion of the spider in the direction of the arrows, from the spider arms 14, as clearly shown in Figure 1. With the discharge-end of the vessel also cut down as indicated at 16, it will be seen that what popped corn has been picked up by a given 100 grid will readily roll off the grid into the vessel 8.

The object of the final cross-bar 15^b of each grid is to sweep the bottom of the vessel, so as to prevent any popping corn 105 kernels from remaining in one place and becoming burned. Ordinarily, the kernels will not be taken along on the up-course of the grid, since they will fall out of the meshes thereof and back into the lower part of the 110 vessel. There may, however, be a number of kernels carried immediately in front of

the cross-bar 15^b in its motion toward the outlet, and to prevent the discharge of these kernels from the vessel I have distended the bottom of the latter at the discharge-end a short distance, as indicated at 5^c. This feature constitutes a departure of the bottom of the vessel from the grid, which with proper spacing will unseat the elevated kernels as the grid approaches the discharge-end of the vessel, permitting such kernels to roll back into the lower part of the vessel. I have finely-dotted in Figure 1 where the true bottom would be, for purposes of distinction.

For a supply of popping corn to the vessel, a hopper 17 may be provided, the same having a lead 18 into the receiving end of the vessel and a suitable flow control 19. This feeding means is but a suggestion on my part as any other means may be supplied to the vessel for the feeding of corn thereto.

It will now be seen that I have provided a very simple machine for the purposes stated. To make the same more attractive to the observer or patron, I would prefer to construct the vessel of heat-proof glass, known as "pyrex". So constructed, the display of the machine with the popping of corn in action will be very alluring and should improve the sale of the product and the business of the establishment. It will be apparent that I have employed no involved or complicated mechanisms to accomplish the purposes of the machine, and increase the cost of the same to an extent beyond the reach of small merchants and confection stand vendors. In other words, my machine is for the popular delicacy establishment or roadside stand, and is constructed so cheaply as to be within the means of the average merchant in that category.

While I have illustrated and described my invention in the preferred embodiment, it will be seen that the same is capable of many minor changes and refinements, and I desire to claim such changes and refinements as coming within the spirit and scope of the appended claims.

I claim:

1. A corn popper comprising a trough, and a sweep arm movable along and in substantial contact with the floor of the trough throughout the major portion of its travel therealong, the floor of the trough diverging tangentially from the path of travel of the paddle toward the end of the path of travel.
2. A corn popper comprising a sector-shaped trough having flat parallel sides, a sweep arm movable along the floor of the

trough, and a paddle member carried by the sweep arm adapted to contact with the floor of the trough throughout the first and greater part of its travel therealong, said floor diverging from the path of travel of the paddle adjacent the end of the travel therealong.

3. A corn popper comprising a trough, a sweep arm movable along the floor of the trough, and a foraminous paddle member carried by the sweep arm formed to leave behind the unpopped corn kernels and take along the popped corn.

4. A corn popper comprising a trough, a sweep arm movable along the floor of the trough, and a paddle member carried by the sweep arm, said paddle member being made with perforations of a size sufficient for the passage of popping corn kernels and less than for the passage of the popped corn, said paddle member having a portion extending the entire width thereof and contacting with the floor of the trough.

5. A corn popper comprising a trough formed with sides and a floor, a rotatable shaft journaled in the sides, and a radial arm carried by the shaft and having rearwardly bent portions adapted to sweep said floor.

6. A corn popper comprising a trough, a sweep arm movable along the floor of the trough, and a paddle member carried by the sweep arm, said paddle member having the formation of a multi-pronged fork with a bar across the ends of the prongs.

7. A corn popper comprising a trough, a sweep arm movable along the floor of the trough, and a paddle member carried by the sweep arm, said paddle member having the formation of a multi-pronged fork with a bar across the ends of the prongs, said bar having a sliding contact with said floor.

8. A corn popper comprising a trough with a floor having receiving and discharge ends, a sweep arm movable along the floor of the trough, and a paddle member carried by the sweep arm, said floor departing from the course of the paddle at its discharge end whereby to become separated from the paddle.

9. A corn popper comprising a trough with sides and a dipped floor with a circular curvature, a rotatable shaft journaled in said sides, a radial sweep arm extending from the shaft, and a paddle member carried by the sweep arm and in sliding contact with said floor and sides.

In testimony whereof I affix my signature.
SWAN NELSON.
